UNITED STATES PATENT OFFICE.

NORBERT M. LA PORTE, OF BALTIMORE, MARYLAND.

INTERNAL-COMBUSTION ENGINE.

1,277,736.

Specification of Letters Patent. Patented Sept. 3, 1918.

Application filed June 29, 1917. Serial No. 177,631.

To all whom it may concern:

Be it known that I, NORBERT M. LA PORTE, a citizen of the United States of America, residing in the city of Baltimore, State of Maryland, have invented certain new and useful Improvements in Internal-Combustion Engines, of which the following is a specification.

All internal combustion engines are provided with, or operate in connection with, a system for distributing oil to the cylinders and engine bearings. In some, the cylinder oil is mixed with the fuel; in others it is fed by means of a pump through suitable channels or passages to the surfaces to be lubricated; and in still others, the oil is placed in the crank case and each crank at the lowest point of its stroke dips into a pool or pocket of oil splashing the oil up on to the connecting rod and piston so that oil is supplied to the bearings and cylinder walls at each stroke. The two latter are known as the force feed and splash systems respectively. In the latter system, the oil pockets into which the cranks dip are generally so arranged that the oil flows backward from one to the other and some means is provided for feeding oil to the front pocket or to the timer gears from which it flows to the front pocket.

These circulating systems with their various reservoirs and passages are referred to herein as "ducts or passages" holding the lubricant and leading it in contact with the surfaces to be lubricated.

In some well-known types of motor cars, there is a funnel or cup in the vicinity of the fly wheel which catches a portion of the oil thrown up from the fly wheel and a tube running from the bottom of the cup downward and forward to the timer gears or forward oil pocket. At normal speeds, a considerable amount of oil is circulated in this way, being thrown up by the fly wheel, caught in the cup, carried forward by the inclined tube and distributed by the splash or flowing backward through a series of pockets until it comes again into the pit or casting in the vicinity of the fly wheel, but at higher engine speeds, particularly where the high speed is maintained as in continuous running on low gear or in the operation of tractors or trucks where the gear ratio is very low, the centrifugal impulse imparted by the fly wheel to the oil is so great

that it is thrown clear of the cup, greatly reducing the oil circulation. Under these circumstances, the cylinders and timer gears do not get sufficient oil and are soon injured requiring frequent repair and replacement. 60

The device of my invention as shown in the present application may be used to supplement other systems for supplying cylinder oil and the like to the bearings and cylinders of an internal combustion motor to 65 increase the oil circulation, to overcome the difficulty described, or for any other purpose, or it may be employed independently as the sole means for circulating the lubricant. 70

To this end, I provide a small reservoir located at or near the bottom of the system or so that the oil flows or drips into the reservoir, preferably by gravity. From this reservoir, a pipe leads to the point or points 75 of lubrication. I also lead to this chamber a portion of the exhaust which furnishes the circulating impulse or energy. I find it most convenient to make the oil reservoir and pipes leading to and from it in the form 80 of an injector as hereinafter described.

In the accompanying drawings I have illustrated several slightly different forms of apparatus embodying my invention, the different forms being selected to illustrate the 85 preferred manner of applying the invention under slightly different circumstances rather than with any view to showing the scope of the invention which is believed to be much broader than the range of apparatus illustrated. 90

In these drawings, Figure 1 is an elevation of an internal combustion engine showing one method of applying my invention;

Fig. 2 is a similar view of practically the 95 same system applied with a sight feed mounted on the dash or instrument board;

Fig. 3 is a longitudinal central section showing the injector member and reservoir by means of which the energy of a portion 100 of the exhaust is imparted to the lubricant to set up and maintain the circulation;

Fig. 4 is an elevation of an engine or motor to which my lubricating system has been applied, the oil reservoir or injector 105 being differently located and the system being supplied with a gravity reservoir and vent at the top of the system;

Fig. 5 is an enlarged elevation at right angles to Fig. 4 looking from the rear at 110

the lower part of the crank case fragmentarily shown to illustrate the manner of applying the injector element;

Fig. 6 is a section showing the gravity 5 reservoir, sight feed and vent; and

Fig. 7 is a vertical central section of the gas pipe connection to the manifold with check valve and adjustment.

Referring to the drawings by numerals, 10 I have shown my invention in each instance applied to an internal combustion engine which is installed as the power plant of an automobile or other self-propelled vehicle. In each instance the crank case 1 is provided 15 with four oil pockets 2, 3, 4 and 5 and a fly wheel chamber 6, the arrangement being that usually adopted with the splash system.

In Fig. 1 I have shown an oil reservoir 20 and injector 7 directly beneath the fly wheel chamber. This injector is connected to the bottom of the fly wheel chamber or casing 6 by a screw connection 8, to the timer gear casing 9 by a tube 10 and to the exhaust manifold by a tube 11.

25 Referring now to Fig. 3, the tubes 10 and 11 are in alinement and in the form of the invention shown, the tube 11 terminates in a nozzle 12 directed into the center of a conical portion 13 of the reservoir 7 which is 30 concentric with and forms an extension of the pipe 10, the construction shown being quite similar to various types of injectors. However, the injector principle is not essential to the broadest conception of my invention which contemplates the utilization 35 of the exhaust in any manner to circulate the lubricant.

It being understood that the crank case 40 normally contains oil to a considerable depth, the operation of the invention may be easily understood. The oil flows into the injector chamber or reservoir 7, preferably by gravity, and when the engine is running, it is forced through the pipe 10 impelled by 45 the portion of the exhaust which enters the chamber through the pipe 11 and the nozzle 12, the gas and lubricant being broken into successive bodies which pass through the pipe like pistons one after the other providing a regular supply of liquid by a force 50 feed and without loss of energy as the utilization of the exhaust in this way cannot in any degree reduce the power of the engine. In fact, to a slight degree, in theory at least, 55 it helps to reduce the back pressure.

In Fig. 2 I have shown the system substantially the same as in Fig. 1 except that in place of the oil pipe 10 leading from the injector to the timer gears, I have shown a 60 pipe 15 leading directly upward to and through the dash or instrument board 16 to a sight glass 17 through which the oil passes to a pipe 18 leading to the timer gear case 9 or to any point in the system to which 65 it is found expedient to deliver the cylinder

oil whence it is to flow or to be distributed to the parts which it is desired to lubricate by means of the ducts or passages provided.

In Fig. 4 I have shown the injector or oil reservoir 7 applied to the fly wheel 70 chamber or casing on the rear side by means of a suitable connection 19 substituted for the lower pet cock 20 shown in Figs. 1 and 2. The reservoir 7 is connected to the exhaust manifold 21 by a tube 11 corresponding 75 to the tube 11 in Figs. 1 and 2, terminating in a nozzle 12 as shown in Fig. 3. In fact, the entire injector, except for the position in which it is connected, may be the same as that illustrated in Fig. 3. For the 80 oil delivery pipes shown in the previous figures, I have substituted an oil pipe 22 which extends upward from the injector to a gravity reservoir 23 on the front side of the instrument board. This chamber, 85 shown in detail in Fig. 6, may be provided with a suitable strainer 24 and a vent 25 which is used when the crank case is so tight that it becomes necessary to provide for the escape of the small amount of gas used to 90 propel the oil. In addition to the gravity chamber 23, I have shown a sight glass 17 which may of course be used with or without the gravity chamber. The oil pipe 30 from the bottom of the gravity chamber or cup 95 23 leads to the top of the sight glass 17 and the oil pipe 25 leads from the bottom of the sight glass to the timer gear case 26 or other suitable point of delivery for the oil.

In Figs. 7 and 4 I have shown an improved fitting 35 connecting the gas pipe 11 to the exhaust manifold. In the preferred embodiment of my invention, this is used in place of the corresponding connection 47 shown in Fig. 1. The fitting shown in Fig. 7 is in two parts, first, a nipple 36 having a conical end 37 to fit the cupped end of the gas pipe and a thread 39 to engage a threaded collar 40 which takes over the pipe end and forces the conical end 37 of the nipple 110 into the cupped end of the pipe, and second, a lower section 43. The nipple is chambered at 41 and intermittently threaded to engage the internal thread of the lower section. This lower section has a valve seat 44 for a ball valve 45 in the chamber 41 to serve as a check to prevent back-flow or siphoning of the oil in case backward flow is started by any means. It will be noted in this connection that the gas pipe extends 115 above the oil level and this arrangement is ordinarily sufficient to prevent back-flow of the oil into the manifold.

In addition to the ball valve 45, the fitting includes a means 46 shown in the form 125 of a screw, for adjusting and reducing the cross-section of the gas passage 48. The adjustment of the passage by the means 46 is to determine the amount of exhaust utilized in propelling the lubricant and hence 130

the velocity of circulation. This fitting, while it is described in connection with an exhaust actuated lubricating system may be applied to any device used in connection with an internal combustion engine - in which the exhaust is used as an actuating means for any purpose.

The operation of the system including the gravity chamber is similar to that already described except that the oil after being carried by the action of the exhaust to the gravity chamber flows by gravity down to the timer case or other point of delivery to the lubricating ducts or passages instead of being carried by the exhaust directly from the reservoir or injector 7 to the timer case to the point of delivery.

While the invention has been illustrated in connection with a splash system, it is obvious that it may be utilized with any internal combustion engine having means for retaining a supply of lubricating oil in contact with the surfaces to be lubricated so that it is available at one point of the system to be carried by the exhaust to another point so as to maintain the circulation in contact with the surfaces to be lubricated as described.

I have thus described my invention specifically and in detail in order that its nature and operation may be fully understood; however, the specific terms herein are used descriptively rather than in their limiting sense and the scope of the invention is defined in the claims:

1. In combination with an internal combustion engine, a duct or passage for holding the oil in contact with the surfaces to be lubricated, means at one end of said duct for receiving oil from said duct, and exhaust actuated means for delivering the oil to the duct near the opposite end of said duct and causing it to circulate continuously during the operation of the engine in contact with the surfaces to be lubricated.

2. In an internal combustion engine in combination, ducts or passages for the circulation of lubricant in contact with the surfaces to be lubricated, an injector for receiving lubricant from said passages near one end of said passages, means for leading a portion of the exhaust gases to the injector utilizing the same as the means for

actuating the injector, and means for leading the oil from the injector and delivering it near the end of said passages, causing the oil to circulate in contact with the surfaces to be lubricated, the oil pipe leading from the injector including a vent for the air and gas.

3. In an internal combustion engine in combination, a duct or passage for the circulation of lubricant in contact with the surfaces to be lubricated, an injector for receiving lubricant from said passage, means for leading a portion of the exhaust gases to the injector utilizing the same as the means for actuating the injector, and means for leading the oil from the injector and delivering it back to said passage at a different point therein, causing the oil to circulate in contact with the surfaces to be lubricated, the oil pipe leading from the injector including a vent for the air and gas above the oil level.

4. In an internal combustion engine in combination, a duct or passage for the circulation of lubricant in contact with the surfaces to be lubricated, an injector for receiving lubricant from said passage near one end of said passage, means for leading a portion of the exhaust gases to the injector utilizing the same as the means for actuating the injector and delivering the lubricant near the other end of said passage causing the lubricant to circulate in contact with the surfaces to be lubricated, the oil pipe including a gravity reservoir with a vent above the oil level.

5. In an internal combustion engine in combination, a splash lubricating system, an injector connected to a low point in the system to receive oil therefrom, means for conducting the exhaust to the injector to actuate the same, and means for conducting the oil from the injector propelled thereby to a point in the system from which it will flow in contact with the surfaces to be lubricated and back to the injector.

Signed by me at Baltimore, Maryland, this 28th day of June, 1917.

NORBERT M. LA PORTE.
